US00D479836S

(12) **United States Design Patent** (10) Patent No.: **US D479,836 S**
Thornton et al. (45) Date of Patent: ** *Sep. 23, 2003

(54) **VOCAL MICROPHONE (PG58 AND PG48)**

6,424,724 B1 7/2002 Ming-Cheng

(75) Inventors: **Brian Thornton**, Tinley Park, IL (US);
Christian J. Kulujian, Chicago, IL (US); **William C. Cesaroni**, Glenview, IL (US)

The ornamental design for a vocal microphone (PG58 and PG48), as shown and described.

DESCRIPTION

FIG. 1 is a perspective view of the microphone design; FIG. 2 is a front view thereof; FIG. 3 is a top view thereof; FIG. 4 is a side view thereof; FIG. 5 is a rear view thereof; and, FIG. 6 is a bottom view thereof.
